Fig-6

The design is intended for use on sets comprising forks, spoons, knives and similar articles of flatware.

I claim:

The ornamental design for a tablespoon or similar article, as shown and described.
